UNITED STATES PATENT OFFICE.

JOHN EUGENE SHOEMAKER, OF WASHINGTON, DISTRICT OF COLUMBIA.

PIANO-PLAYING ATTACHMENT.

No. 901,562.

Specification of Letters Patent.

Patented Oct. 20, 1908.

Application filed February 15, 1906, Serial No. 301,196. Renewed March 14, 1908. Serial No. 421,086.

To all whom it may concern:

Be it known that I, JOHN EUGENE SHOEMAKER, residing at Washington, in the District of Columbia, have invented a new and useful Piano-Playing Attachment, of which the following is a specification.

My invention relates to automatic piano playing attachments.

It has for its object to simplify the construction of the operating mechanism, adapted for use in either an exterior piano playing attachment, or for attachments constructed within the casing of the piano.

Another object of the invention is to so construct the operating mechanism that it may be easily taken apart for adjustment, repairs and for the replacement of parts.

Referring to the drawings: Figure 1 is a cross sectional view of a piano playing attachment embodying my invention. Fig. 2 is a front elevation of the casing containing the exhaust chamber, the primary pneumatics and the valve operating mechanism, parts being broken away to show the interior construction. Fig. 3 is a cross sectional view on line 3—3 of Fig. 2 on a somewhat larger scale. Fig. 4 is a perspective view of the valve plate and valves for the exhaust and inlet ports. Fig. 5 is a perspective view of a valve plate and valves showing another form of rocker member.

In the drawings, A represents the exhaust bellows, which may be of any preferred form and provided with suitable valves, and B the pedal, for operating the exhaust bellows, connected thereto by links a, b.

2 indicates a casing comprising the pieces 2', 2'', and front board or cover 3, which is removable or hinged at its lower edge to 40 permit access to the interior of the casing, as hereinafter set forth. The casing is closed at its sides and forms the exhaust chamber for the mechanism so as to operate the power pneumatics C. The cover is locked in position by screws or other means.

4 indicates the valve boxes which are arranged in tiers as shown in Figs. 1 and 3. These valve boxes extend through the rear side 2'' of the exhaust chamber casing in order that the exhaust valve 6, mounted therein, may be directly above the primary pneumatic 5. The primary pneumatics are supported in longitudinally arranged bars extending from end to end within the casing.

55 The primary pneumatics are connected with the flexible tubes d by ducts suitably

arranged in the bars 4'. The rubber tubes d extend upward through the exhaust chamber, and through apertures cut in the top of the casing, to the tracker board. 60

By this construction it will be seen that all of the parts are compactly arranged and at the same time are in such position that they may be easily reached for repairs or the like.

Mounted within the valve box are two right members 9, 9, to which are fulcrumed a rocker member 8. To one end of the rocker member is secured the exhaust valve 6 which is operated by the primary pneumatic valve 5 to control the exhaust port 6''. On the opposite end of the rocker member is secured a valve 7 arranged to open and close a port 7'' leading to the atmosphere. 65

The valve boxes 4 are connected by a passage way or duct 11 with the power pneumatics C whereby power is applied to some operating part of the piano for operating the hammers thereof. 75

To permit access to the valves arranged within the valve box, one side thereof, preferably the front side, is made removable. The removable member consists of strips or pieces 12, which extend longitudinally of the casing. These strips or closing pieces are held in position by the screws 12'. 80

13 indicates a plate on which the upright members 9, 9, carrying the rocker member 8 and valves 6 and 7, are mounted. This plate is provided with valve seats 6', 7' corresponding with the exhaust port 6'' and inlet port 7''. The plate 13 is made removable, guide-ways 13', 13' being provided in the sides of the valve box 4 so that the plate may be taken out and returned to proper position. In order to assist in the operation of the 90 rocker member, I provide a spring 8' between one arm thereof and the plate, as shown in Fig. 4. 85

In the form of the invention shown in Fig. 5, the rocker member 14 consists of a metal rod bent at right angles at its opposite ends on which the valves 15, 16 are mounted. The ends of the rod are provided with screw-threads 15' adapted to engage screw-threads in the valves whereby the latter may be adjusted relative to their seats. By making the rocker member of metal, the ends may be readily bent so as to cause the valves to rest properly on their seats if they get out of alignment. In this form of the invention I 110 prefer to make one of the valves heavier than the other to assist in the operation thereof. 105

As shown in the drawings, the several parts of the pneumatic operating mechanism are all arranged within a single casing, which casing is formed with a chamber in which the air is exhausted to operate the pneumatics. The casing may be of any size or shape to adapt it for use in an interior piano player, or it may be constructed within an exterior piano playing attachment.

10. What I claim is:

1. In a playing attachment, the combination with the tracker board, of an exhaust chamber, the primary pneumatics mounted within the exhaust chamber, a series of valve boxes mounted within the said exhaust chamber, a series of power pneumatics, and connections leading from the said primary pneumatics to the tracker board.

2. In a playing attachment, the combination with the tracker board, of an exhaust chamber, the primary pneumatics mounted within the exhaust chamber, a series of valve boxes mounted within the said exhaust chamber, a series of power pneumatics, and connections leading from the primary pneumatics through the exhaust chamber to the tracker board, substantially as set forth.

3. In a playing attachment, the combination with the tracker board, of an exhaust chamber having a removable cover, bars extending longitudinally from end to end within the said exhaust chamber, the primary pneumatics mounted in said bars, conduits arranged to connect the primary pneumatics with the tracker board, valve boxes mounted within the said exhaust chamber, the power pneumatics, and connections between the valve boxes and the power pneumatics, substantially as set forth.

4. In a self playing attachment, the combination of an exhaust chamber, a primary pneumatic mounted within the said chamber, a power pneumatic, a valve box, one end thereof extending into the exhaust chamber and provided with an exhaust valve, and the opposite end leading to the power pneumatic, an inlet valve adapted to communicate with the atmosphere, and a

rocker connecting together the said exhaust and inlet valves, substantially as set forth.

5. In a self playing attachment, the combination of an exhaust chamber, a primary pneumatic mounted inside of said chamber, a power pneumatic, a valve box, one end thereof extending into the said exhaust chamber and the opposite end connected with the power pneumatic, an exhaust valve and an inlet valve mounted within the valve box and arranged in the same horizontal plane, a rocking member connecting the said valves together, and a plate provided with valve seats and arranged to pivotally support the rocking member, substantially as set forth.

6. In a self playing attachment, the combination with the tracker board, of an exhaust chamber, a primary pneumatic mounted therein, a power pneumatic, a valve box, one end of which extends within the said exhaust chamber and provided with an exhaust valve arranged vertically relative to said primary pneumatic, and the opposite end connected with the power pneumatic, and being provided with an inlet valve, the said exhaust and inlet valves being arranged in the same horizontal plane, and a tube leading from said primary pneumatic through the exhaust chamber to the tracker board, substantially as set forth.

7. In a playing attachment, the combination of a casing provided with a cover, a primary pneumatic mounted therein, a valve box having one end extending into said casing and provided with an exhaust valve, a power pneumatic connected with the opposite end of the valve box, an inlet valve for admitting atmosphere in said valve box, a removable strip for the end of the valve box that extends into the casing, arranged directly behind the cover thereof, and means for exhausting the air in the said casing, substantially as set forth.

JOHN EUGENE SHOEMAKER.
